UNITED STATES PATENT OFFICE.

HALFORD W. PARK, OF SCARSDALE, NEW YORK, ASSIGNOR TO ROCKWOOD SPRINKLER COMPANY OF MASSACHUSETTS, OF WORCESTER, MASSACHUSETTS, A CORPORATION OF MASSACHUSETTS.

AUTOMATIC VALVE FOR DRAINING VARIABLE-PRESSURE ALARM SYSTEMS.

Application filed December 31, 1921, Serial No. 526,429. Renewed March 13, 1925.

To all whom it may concern:

Be known that I, HALFORD W. PARK, a citizen of the United States, residing at Scarsdale, in the county of Westchester and State of New York, have invented a new and useful Automatic Valve for Draining Variable-Pressure Alarm Systems, of which the following is a specification.

This invention relates to an automatic device for controlling the supply and discharge of water under pressure for operating an alarm or the like.

The principal objects of the invention are to provide means which will insure that when the alarm valve check lifts from its seat all the water discharged through the pipe and spaces connecting the annular port of the alarm valve with the alarm actuating mechanism will be utilized for alarm purposes, without waste, and to provide means which will insure that when the check closes, the water thereby left trappel in the alarm valve system will be drained forthwith leaving the alarm valve connecting pipe and spaces in their normally empty condition and thus automatically ready for further operation; to provide a construction in which, although both of the above objects are attained, no alarm will result from the uncovering of the annular port as the effect of mere water hammers transmitted to the alarm valve through the water in the system; to provide a system in which there are no moving parts except a float valve, nothing to create friction and nothing to corrode; and to provide these features in such form as to be practically applicable to a fire sprinkler system.

Further objects and advantages of the invention will appear hereinafter.

Reference is to be had to the accompanying drawing which is a sectional view of a part of a water alarm system showing a preferred form of this invention applied thereto.

I have shown the invention as used in connection with a variable pressure alarm valve 10, when the valve 10 opens, water will flow as usual through a pipe 13, the end of which is connected with an annular port 12 in the valve seat which is normally closed by the alarm valve 10. The pipe 13 is shown as feeding the usual water motor alarm device 16 adapted to be operated by

the flow of water through the pipe 17 to 85 sound the gong when the valve 10 opens.

This invention involves means by which all the water that flows by the valve 10 through the pipe 13 will be delivered into the pipe 17 and alarm motor system without 60 waste and when the alarm valve 10 closes again the water will immediately discharge into the atmosphere at a rapid rate.

Extending downwardly from the pipe 13 into the bottom of a suction chamber 23 65 is a chamber 21 shown in the form of a pipe. In these chambers 21 and 23 is a body of heavy liquid, preferably mercury 24, which, when there is no pressure, will come to the same level in the two chambers. 70 Floating in the mercury in the chamber 23 is a float 27 which can be made of cast iron, weighted with lead, if desired, and provided with a valve 29 at the top. Just above this valve is a valve seat 26, having 75 a large port 30 through it. This port communicates with a discharge pipe 32 at the top for discharging water from the system into the open air.

Also communicating with the top of the 80 suction chamber 23 there is a pipe 33 leading into the pipe 13. At the top of this, in the pipe 13 just at the pressure side of the pipe 33, there is a thin partition plate or obstruction 35 having a restricted 85 orifice 34.

When water is flowing through the pipe 13, its full pressure will be exerted on the mercury in the pipe 21. There will, however, be less pressure on the suction chamber 90 23 due to the fact that the pipe to the suction chamber is connected to the flow pipe at a point just back of the thin plate. At this point in the pipe, there is a greatly reduced pressure due to the fact that the flow 95 of the water through the orifice is restricted. Therefore as is well understood, under certain conditions as to pressure, size of pipe and size of orifice, there will be a partial vacuum just beyond the plate. This difference in pressure is used to operate the valve 29 by the rise of the mercury in the chamber 23.

When the clapper of the main alarm valve 10 is shut and the system is drained there is very 105 little hydrostatic pressure on the surfaces of the mercury in the two chambers 21 and 23 and what there is is equal, so these surfaces

are at the same elevation. The valve 29 therefore remains in its lowest position leaving the port 30 open to the atmosphere.

Whenever the valve 10 opens and the water starts to flow into the pipe 13, the action of this flow of water unbalances the pressure in the two chambers 21 and 23 in two ways. The unbalancing of the pressure is caused by two forces assisting each other. The first force is the difference in the hydrostatic pressure on the two chambers. The pressure on the mercury on the pipe 21 is greater than the pressure on that in the suction chamber 23 because the former is a closed chamber while the latter is open to the atmosphere. The second force is the difference in pressure on the two chambers due to the reduced flow through the orifice 34. The velocity of the water through the pipe 13 causes a reduction in pressure on the pipe 33 connected to the float chamber which reduction in pressure is transmitted to the surface of the mercury. Either the difference in the force of the hydrostatic heads alone, or the difference in velocity head alone will cause the float to rise. The valve having once risen it will remain on the valve seat holding the port 30 closed as long as water is flowing in the pipe.

As soon as the water flow stops, however, the difference in velocity head disappears and the hydrostatic heads on the two chambers become equal, as long as the valve 29 is closed, so that the mercury in each chamber falls back to the original levels. Then the only force holding the float up to the valve seat is the hydrostatic pressure due to the head of water from the water motor acting on the port 30. The cast iron weight is heavy enough so that this head will not support it and it falls back into its original position in the mercury leaving the port open and free to drain the system, which completes the operation. It will be noted that when the float valve seats on the port, then the hydrostatic head on each chamber becomes equal as both chambers become closed to the atmosphere. Therefore, were it not for the restricted orifice 34 the valve would fall away from the port. The difference in velocity head due to that is the force that holds the valve on the seat while water is flowing.

It is to be observed that while the pipe 17 is filling the force holding the float valve on its seat continually increases until the maximum force is obtained when the pipe to the water motor nozzle is completely filled. If there should be a slight leak around the valve 29 while seated it would not affect the operation of the alarm. It is to be noted that there are no moving parts in the device except the float and nothing to present any friction or to make it possible for the parts to corrode or fail to operate.

It depends solely and directly upon the laws of hydrostatics.

A diaphragm or other equivalent device can be substituted for the mercury as set forth in the claims.

Although I have illustrated and described only a single form of the invention. I am aware of the fact that modifications can be made therein by any person skilled in the art without departing from the scope of the invention as expressed in the claims. Therefore, I do not wish to be limited to all the details of construction herein shown and described but what I do claim is:—

1. In an alarm system, the combination with an alarm motor and a pipe for conducting water thereto, of a restricted orifice within said pipe, a chamber below the pipe communicating at the top with said pipe close to the low pressure side of said orifice and constituting a suction chamber and having an outlet port, the bottom of said chamber communicating with the pipe on the other side of the orifice, a valve in the suction chamber adapted to rise therein and close the port, and means for transmitting the variation in pressure due to the velocity of water past the restricted opening to the top and bottom of said chamber and to said valve to cause it to be elevated and seated.

2. In an alarm system, the combination with an alarm adapted to be operated by the flow of water thereto, means for conducting water to the alarm comprising a conduit, an outlet connected with said conduit, a valve for closing said outlet, means for operating the valve, said conduit having an obstruction therein provided with a restricted orifice whereby suction is produced just beyond the orifice when water flows through the conduit to the alarm, and means whereby the suction is transmitted to the valve to close and hold it closed while the water is flowing.

3. In a device of the character described, the combination with a conduit for conducting water to a water motor, of an obstruction across said conduit having a restricted orifice through it, two communicating chambers below the conduit, each communicating with the conduit on opposite sides of said obstruction and having a body of heavy liquid therein, one of said chambers constituting a pressure chamber communicating with the conduit on the side of said obstruction toward the source of pressure in the conduit, the other chamber having an outlet opening at the top and also communicating with the conduit on the other side of said obstruction, and a valve in the second chamber floating on the liquid therein adapted to rise therein and close the port, whereby the suction due to the velocity of water through the orifice at the top of the suction chamber will act on the

heavy liquid to cause said valve to be seated.

4. In a device of the character described, the combination with a conduit for conducting water to a water motor, of an obstruction in said conduit having a restricted orifice, two chambers below the conduit each communicating with the conduit on one side of said obstruction, and communicating with each other at the bottom, one of said chambers constituting a pressure chamber and the other a suction chamber, a body of mercury in the two chambers, and a valve in the second chamber floating on the mercury and adapted to rise therewith and close the port.

5. In a device of the character described, the combination with a pipe for conducting water to a water motor, of an obstruction extending across said pipe and having a

restricted orifice therethrough, two chambers below the pipe, each communicating with it on one side of said obstruction, one of said chambers connected with the pipe on the pressure side of the obstruction constituting a pressure chamber, the other chamber having an outlet opening at the top and also communicating with the pipe on the other side of said obstruction at a point close to the plate, a valve in the second chamber adapted to rise therein and close the outlet port, and movable means in the two chambers for moving the valve up and down in accordance with any difference in pressure in them.

In testimony whereof I have hereunto affixed my signature.

HALFORD W. PARK.
